(57) **CLAIM**

The ornamental design for the electromagnetic lock, as shown and described.

DESCRIPTION

FIG. 1 is a perspective view of an electromagnetic lock showing our new design;

FIG. 2 is a front view thereof;

FIG. 3 is bottom view thereof;

FIG. 4 is a back view thereof;

FIG. 5 is a right side view thereof; and,

FIG. 6 is a left side view thereof.

The portions of the drawings shown in broken lines represent environmental structure and form no part of the claimed design.

1 Claim, 4 Drawing Sheets

FIG. 1.

FIG. 2.

FIG. 3.

FIG. 4.

FIG. 5.

FIG. 6.
